BRICK SCRIBING AND MARKING DEVICE

Lewis A. Wooten, Barth, Fla.

Application January 23, 1951, Serial No. 207,379

2 Claims. (Cl. 33—32)

1

This invention relates to scribing and marking tools used primarily by bricklayers or masons for marking the angle of the end of a brick, and in particular this invention includes a rectangular shaped frame having a brick receiving opening therein and a flange on one end, and a straight edge having an elongated slot therein and a scribe or marker thereon positioned across the face of the frame and secured in adjusted position by thumb nuts on screws.

The purpose of this invention is to provide means for accurately marking the correct angle on the ends of bricks, in arch building whereby, when the angle is determined, a plurality of bricks may be marked or cut on the same angle.

In constructing a brick arch bricklayers are required to measure the bottom length of a brick and also the top length and these dimensions are laid out on a brick with a sloping line connecting the ends thereof. The brick is then cut and as bricks often shatter or break at unexpected places it is necessary to take the same measurements a second time in order to mark a second brick. With this thought in mind this invention contemplates a tool having a straight edge mounted on a frame whereby with a flange at the end of the frame positioned against the end of the last brick laid next to the arch the straight edge is set to the exact angle and also to the exact length of the next brick. The frame is then placed against the end or side of a brick and the bricks marked by a scribe on the straight edge.

The object of this invention is, therefore, to provide means for forming a marking tool whereby the length of the brick and also the angle of the outer end thereof may readily be determined and also whereby the line may be marked on a brick indicates the length and angle of the extended end of the brick.

Another object of the invention is to provide a tool for marking bricks for arches that is designed to be used in combination with bricks now in use.

A further object of the invention is to provide a tool that may readily be set to indicate the length of a brick and also the angle of the end thereof which is of a simple and economical construction.

With these and other objects and advantages in view the invention embodies a substantially rectangular shape plate with a flange extended from one end, with an opening through the intermediate part thereof, the width and length of which are equal to the width and length of a

common brick and also having an extended slot therein extended across the upper and lower edges, also across one end, and extended to a point substantially midway of the width of the plate at the opposite end, a bar having an elongated slot therein slidably mounted on screws extended through the slots of the plate and bar and having thumb nuts on the outer ends, and a scribe carried by the bar and positioned to engage the edge of a brick corresponding with the opening through the plate.

Other features and advantages of the invention will appear from the following description taken in connection with the drawings wherein:

15 Figure 1 is a front elevational view of the tool showing the scribing or marking plate positioned at an angle in relation to the frame.

Figure 2 is a plan view of the tool shown in Figure 1.

20 Figure 3 is a cross section through the tool taken on line 3—3 of Figure 1.

Figure 4 is a side elevational view showing the scribing units with parts of the bar broken away.

25 Figure 5 is a cross section through the scribing unit and bar, taken on line 5—5 of Figure 1.

Referring now to the drawings wherein like reference characters denote corresponding parts the brick measuring and marking tool of this invention includes a frame 10, a bar 11, screws 12 and 13 which are provided with thumb nuts 14 and 15 and a slider 16, which provides a marker or scribe.

The frame 10 is provided with a centrally positioned opening 17, the width and length of which correspond with similar dimensions of a brick upon which the tool is used and the border of the frame is provided with an elongated slot 18 that extends from a point 19 at one end of the upper section of the frame, across the upper section, downwardly through an end section 20 and across a lower section to the end 21. From the lower part of the end 21 the slot extends upwardly to a point 22. The end 21 of the frame is provided with a flange 23 that is positioned to engage the end of the last brick laid next to the line of the arch when the device is used for marking bricks for an arch.

The screws 12 and 13 are provided with heads 24 and 25, respectively and with the screws slidably positioned in the slot 18, and extended through a slot 26, in the bar 11, the thumb nuts 14 and 15 are placed on the outer ends. The nuts may be positioned with the bar free to slide longitudinally or the bar may be clamped in

position and the scribe or marking member actuated longitudinally on the bar.

The scribe or marking member 16, as illustrated in Figure 4 is provided with a thumb projection 27 to facilitate actuating the member and the opposite surface may be provided with points 28 and 29. It will be understood that the scribe or marking member may be of any type or design and also that a knife, trowel, or other device may be used for marking the bricks.

With the device formed in this manner the flange 23 is placed against the last brick placed next to the arch and the bar 11 is set in the correct position to indicate the length of the next brick and also to the correct angle for scribing the brick the edge of which is then placed in the opening 17, the size of which corresponds to the size of bricks used in the arch, and with the brick held in position the marker or scribe is actuated or a line placed on the brick with the edge of the bar 11 used as a guide.

It will be understood that modifications may be made in the design and arrangement of the parts without departing from the spirit of the invention.

What is claimed is:

1. A brick scribing tool comprising a rectangular shaped frame having side and end bars with a flange extended from one of said end bars and with a slot extended through the side bars, one of the end bars and to a point midway of the length of the other end bar, pins having heads

on one end and threads on the other slidably mounted in the slot of the frame, a bar having an elongated slot therein slidably mounted on the pins, and thumb nuts threaded on the pins for securing the bar having the elongated slot therein in adjusted positions.

2. A brick scribing tool comprising a rectangular shaped frame having side and end bars with a flange extended from one of said end bars and with a slot extended through the side bars, one of the end bars and to a point midway of the length of the other end bar, pins having heads on one end and threads on the other slidably mounted in the slot of the frame, a bar having an elongated slot therein slidably mounted on the pins, thumb nuts threaded on the pins for securing the bar having the elongated slot therein in adjusted positions, and a marking element slidably mounted on the bar having an elongated slot therein.
